Primary Examiner — Amy C Wierenga*(74) Attorney, Agent, or Firm* — Erickson Kernell IP, LLC; Kent R. Erickson(57) **CLAIM**

I claim the ornamental design for a strainer, as shown and described.

DESCRIPTION

FIG. 1 is a front view of a strainer showing my new design; FIG. 2 is a rear view thereof; FIG. 3 is a left-side view thereof; FIG. 4 is a right-side view thereof; FIG. 5 is a top view thereof; FIG. 6 is a bottom view thereof; FIG. 7 is a front perspective view thereof; and, FIG. 8 is a bottom perspective view thereof. The broken lines shown in the drawings illustrate portions of the strainer that form no part of the claim.

1 Claim, 8 Drawing Sheets(56)
